UNITED STATES PATENT OFFICE.

JOSEPH MARX AND JOSEPH H. MUELLER, OF CROSS PLAINS, WISCONSIN.

WAGON-BOX LOCK.

SPECIFICATION forming part of Letters Patent No. 355,459, dated January 4, 1887.

Application filed October 25, 1886. Serial No. 217,128. (No model.)

To all whom it may concern:

Be it known that we, JOSEPH MARX and JOSEPH H. MUELLER, both of Cross Plains, in the county of Dane and State of Wisconsin, have invented a new and Improved Wagon-Box Lock, of which the following is a specification, reference being had to the annexed drawings, forming a part thereof, in which—

Figure 1 is an end view of a wagon-box with our improved lock applied. Fig. 2 is a plan view of the lock detached from the wagon-box; and Fig. 3 is a plan view of a portion of a wagon-box, showing the lock in position for removal from the box.

15 Similar letters of reference indicate corresponding parts in all the views.

The object of our invention is to provide a simple and efficient fastening or lock for the end-gates of wagon-boxes, which may be 20 quickly applied and readily removed.

Our invention consists in two T-headed rods pivoted to the ends of the shorter arms of a T-lever, and a pawl connected with the longer arm of the T-lever, adapted to engage notches 25 in one of the T-headed rods, all as hereinafter more fully described.

The rods A B are provided at their outer ends with T-shaped heads a, and are pivoted at their inner ends to the shorter arms b b' 30 of the T-shaped three-armed lever C. The lever C is arranged to swing in a plane at right angles to the heads a, and to the longer arm of the lever C is pivoted a pawl, c, having at its free end an eye, d, which surrounds the rod 35 A, and is adapted to engage a series of ratchet-teeth, e, formed on the edge of the rod.

In the cleats f of the end-gate D, and in the sides of the wagon-box, are formed mortises g, (shown in dotted lines in Fig. 1,) through which 40 the heads a of the rods A B may be passed. The sides of the wagon-box are provided with plates h, having apertures corresponding to the mortises g, for receiving the pressure of the heads a.

45 The lock is applied to the wagon-box by arranging the lever C at right angles to the end-gate and sliding the head a of the rod B

through the mortise g, as shown in dotted lines in Fig. 3, until the head a of the rod A can be inserted in the mortises g of the opposite side of the end-gate of the wagon-box, when the lock is slid in the opposite direction, bringing the heads a on opposite sides of the wagon-box. The lever C is then turned down into a vertical position, bringing the heads a at 55 right angles to the mortises g. The lever C is then swung around so as to draw the ends of the rods A B together, as shown in dotted lines in Fig. 1, thus clamping the sides of the wagon-box firmly against the ends of the end-gate. The pawl c engages the ratchet-teeth e of the rod A and holds the lever C in the position in which it is placed. When it is desired to unfasten the end-gate, the pawl c is disengaged from the ratchet-teeth e, and the 60 rods A B are removed from the mortises by reversing the operation just described.

The device which we have described in connection with the end-gates of wagons may be applied to the straining of saw-frames.

Having thus fully described our invention, we claim as new and desire to secure by Letters Patent—

1. The combination of the rod A, provided with the T-shaped head a and ratchet-teeth e, 75 the rod B, provided with the T-shaped head a, the T-shaped lever C, pivotally connected with the rods A B, and the pawl c, pivoted to the lever C and adapted to engage the ratchet-teeth e, substantially as described. 80

2. The combination, with the wagon-box and end-gate provided with mortises g and plates h, of the rod A, provided with the head a and ratchet-teeth e, the rod B, provided with the head a, the T-shaped lever C, pivotally connected with the rods A B, and the pawl c, pivoted to the lever C and adapted to engage the ratchet-teeth e, substantially as described.

JOSEPH MARX.

JOSEPH H. MUELLER.
